RAM JET PROPELLER**Constantine A. Serriades, 732 Bittersweet Place,
Chicago, Ill.****Filed Nov. 28, 1955, Ser. No. 549,360****5 Claims. (Cl. 170—135.4)**

This invention relates to an improved type of jet propelled propeller structure. Specifically this invention relates to a jet propelled propeller structure having a two-stage centrifugal flow compressor integral with the propeller hub as a means for supplying an additional velocity increment to air passing through the hollow blade portions of the propeller structure.

In conventional propeller driven aircraft, the propeller and engine are separate components in the thrust producing system for the aircraft. This independent unit type of construction has necessarily resulted in a power package of considerably great weight and bulk as compared to the weight of the propeller structure itself. The additional weight of accessories, control system, and a suitable gear reduction device between the propeller structure and engine, accounted for a very substantial part of the non-pay load weight of the aircraft. It thus becomes readily apparent that any proposed power system which could integrate the propeller and engine as a single structure would produce substantial weight savings due to the elimination of many of the separate drive and control components, necessary for the separate propeller-engine type of construction.

Various integrated propeller-jet propulsion systems have been proposed from time to time as a solution to the problems above mentioned, but for the most part these systems have only been a combination of a conventional propeller and some form of separate jet propulsion device. A common example of this is the application of the ram jet engine to the tip of a propeller blade or rotor, such as is used in some experimental helicopters. Actually, most of the propeller-engine combinations currently in use are only a combination of a conventional propeller and jet engine, each unit retaining its individual form and function.

The present invention discloses an entirely novel form of integrated propeller-jet propulsion system in which the propeller structure itself becomes part of a jet engine. By thus integrating the component parts and functions of the formerly separate jet engine and propeller, substantial advantages result in the form of a great reduction in weight of the combination structure, simplicity of construction and maintenance, and an overall improvement in efficiency and control.

Briefly described, the present invention contemplates a generally conventional propeller structure having two or more hollow blades having an air inlet or series of inlets in the leading edge of one or more of the blade elements, substantially near the blade tip, and a jet exhaust outlet or nozzle in the trailing edge of one or more of the blade elements, serving to direct a jet exhaust out of the blade nozzle tangential to the blade path, as a rotative power source for the propeller.

The hollow hub portion of the propeller, in addition to retaining the blades in proper aerodynamic relationship and housing a pitch control device, also includes a two-stage centrifugal flow compressor, receiving air from the

2

inlet, or inlets, in one or more of the blades, thereby supplying an additional velocity increment to the air moving out of the second stage compressor toward the jet exhaust outlet in the rotative thrust producing blade. The compressor elements of the two-stage centrifugal flow compressor are preferably of the double-entry, back-to-back type, the outlet of the first stage compressor element feeding the inlet or eye of the second stage compressor element, though a single sided compressor blade cascade might be used in some particular installations. Air passing through the inlet and down the hollow blade toward the hub, will thus receive an additional pressure and velocity increment before passing through the jet exhaust outlet nozzle.

15 Provision is also made in the thrust producing blade element for the addition, mixing and ignition of fuel, as an additional means of augmenting the jet velocity out of the jet nozzle in the thrust blade element. Furthermore, a substantial velocity increment is added to the air in 20 the thrust producing blade element as it moves toward the jet exhaust outlet nozzle, due to the centrifugal force effects from the rotation of the propeller assembly.

The provision for a two-stage centrifugal flow compressor in the hub of the propeller assembly also greatly extends the operating range and applications of the present invention, in that a much lower propeller speed can be maintained without danger of failure of the integral jet propulsion system, due to the large velocity increment imparted to the air as it passes through the two-stage centrifugal flow compressor in the hub of the propeller.

25 Thus it will be appreciated that the present invention discloses a novel type of combined propeller and integrated jet propulsion system which overcomes the disadvantages of excessive weight, bulk, control, and maintenance problems, usually attributed to a separate component type of construction, and at the same time presents an extremely versatile power package for conventional propeller driven aircraft.

30 In addition, the present invention is easily adaptable or usable, as a supplementary or secondary power source with a conventional engine, where a wide range of operating speeds and flight conditions are expected. Use of the present invention in conjunction with a conventional engine would make possible a much smaller primary engine unit, the integral jet propulsion system of the present invention being adequate to maintain normal flight and 35 cruising speed once a desired altitude is reached. Substantial fuel savings could be expected when using the instant invention in conjunction with a conventional engine, particularly at high altitudes, where the jet propulsion system becomes substantially more efficient than a reciprocating engine.

40 The present invention will thus serve to increase the useful operating range, cruising speed, ceiling and generally add to the utility of a conventional propeller driven aircraft when used as a primary power source or in conjunction with a conventional engine.

45 It is an object then of the present invention to provide an improved type of propeller utilizing an integrated jet propulsion system as a rotative power source.

50 Another object of the present invention is to provide an improved jet-propelled propeller structure, in which a rotative type compressor is utilized to additionally pressurize air moving through the internal passages of the propeller structure which form a jet flow passage therethrough.

55 A further object of the present invention is to provide a method of imparting an increased velocity increment to air moving through the hollow internal portions of a propeller blade, which forms a jet propulsion flow passage, in addition to the velocity increase resulting from the 60 centrifugal force of the blade rotation as the air moves toward a jet exhaust outlet in the blade tip.

Another object of the present invention is to reduce the weight of the power-package of propeller driven aircraft.

Yet another object of the present invention is to provide an improved type of jet propelled propeller which overcomes the deficiencies of the prior art where the centrifugal force of the rotating propeller is utilized as a means for pressurizing air in the integral jet propulsion system of the blade.

A still further object of the present invention is to provide an improved type of jet propeller structure which greatly simplifies the control maintenance and construction problems associated with the separate propeller engine type of construction.

Many other objects and advantages of the present invention will become manifest to those versed in the art upon making reference to the detailed description which follows and the accompanying sheets of drawings.

On the drawings:

Figure 1 is a somewhat broken elevational view, partially sectional and diagrammatic, with some parts omitted to show underlying parts;

Figure 2 is an enlarged fragmentary view, partially sectional and diagrammatic, illustrating the compressor assembly in the hub; and

Figure 3 is a cross-sectional view, with parts in elevation, along the line III—III of Figure 1.

As shown on the drawings:

In the embodiment of the invention illustrated in Figure 1, a three bladed propeller assembly is shown, designated generally by the reference letter P.

The propeller assembly P is comprised of a hollow hub member 10, which receives a plurality of blades A, B, and C. The blades A, B and C are rotatably secured to the hub 10 so as to permit a limited amount of angular displacement about their longitudinal axes, in response to a pitch control device, not shown. The hub 10 also includes fuel and ignition conduits, not shown, and a two-stage centrifugal flow compressor assembly D whose purpose and function will be more fully explained later.

In Figure 1, the blades A, B and C are hollow and have a plurality of radial flow passages 11a-c formed therein. The radial flow passages 11a-c communicate at their hub end with a centrifugal flow compressor assembly D in the hub 10, and at their blade tip end with a pair of tangential air inlet scoops 12a and 12b and a tangential jet exhaust outlet 13c, respectively.

The blades A, B and C also include leading edge portions 14a-c and trailing edge portions 16a-c. The air inlet scoops 12a and 12b are positioned in the outer periphery of the blades A and B, in the leading edge portions 14a and 14b, respectively, and serve to turn a high velocity stream of air into the radial flow passages 11a and 11b. A plurality of guide vanes 17a and 17b in the air inlets 12a and 12b, reduce the turbulence and energy losses of the high velocity air entering the radial flow passages 11a and 11b.

It should be appreciated that the radial flow passages 11a and 11b are so formed as to minimize duct losses and the centrifugal force effects on air in the passages moving toward the hub 10, due to the rotation of the propeller assembly P.

The blade C includes the jet exhaust outlet 13c in the trailing edge 16c of the blade, which is in communication with the radially accelerating exhaust passage 11c. The jet exhaust outlet 13c is in immediate registry with a combustion chamber 18, formed in the tip of the blade C, at the end of the accelerating exhaust passage 11c.

A flame holder 19 and spark gap 20, immediately upstream of the combustion chamber 18 serve as a starting and main fuel ignition means for the jet combustion process in the combustion chamber 18. A fuel injector or spray 21, substantially upstream of the flame holder 19 serves as the main fuel supply source, and receives fuel connecting conduits 22 in the solid portion of the blade

C. A series of baffles or agitators 23 are positioned in the accelerating exhaust passage 11c immediately downstream of the main fuel injector 21 to insure an adequate mixing of the fuel-air mixture entering the combustion chamber 18.

It will thus be appreciated, that the blades A and B form the inlets, and that the blade C forms the exhaust outlet, for an integrated jet propulsion system in the propeller assembly P.

It should further be appreciated that while a three bladed propeller assembly is shown in Figure 1 having two inlet blades and a single exhaust blade, many variations in the number and arrangement of inlet and exhaust outlets are possible depending on the application of the principal invention.

Referring now to Figure 2 in conjunction with Figure 1, a two-stage centrifugal flow compressor assembly D is enclosed in the hollow central portion of the hub member 10. The two-stage centrifugal flow compressor assembly D is comprised of a pair of centrifugal rotors 26a and 26b, which are in registry with the decelerating radial flow passages 11a and 11b, respectively, and receive initially pressurized air therefrom.

The first-stage compressors 26a and 26b are enclosed 25 by a pair of volutes 27a and 27b, the compressors being preferably of the double entry type, but it should be understood that any other type of compressor might be used depending on the particular application of the principal invention. A pair of diffuser rings 25a and 25b

30 surround the compressors 26a and 26b respectively, and serve to initially impart a vortex flow to high velocity air leaving the vanes of the compressors 26a and 26b. The volutes 27a and 27b are so formed as to divide the air flow moving down the passages 11a and 11b toward the 35 hub 10, so as to permit an axial entry into the first-stage compressor rotors 26a and 26b. Internal guide vanes, not shown, are also provided in the volutes 27a and 27b to minimize any losses around the compressor rotors 26a and 26b.

40 The volutes 27a and 27b have diffuser horns 28a and 28b to provide a pressure recovery for high velocity air leaving the compressors which alternately communicate with either eye of a second-stage compressor rotor 29, so as to form a two-stage compressor assembly.

The second-stage compressor rotor 29 is similar to the first-stage compressors 26a and 26b, but is slightly larger to accommodate the discharge of both of the first-stage compressors when operating at full output. A diffuser ring 30, similar to the diffuser rings 25a and 25b, surrounds the second-stage compressor 29 and also serves to initially channel the flow from the compressor 29 into a surrounding volute 31. A plurality of internal guide vanes in the volume 31, not shown, also serve to minimize any duct losses around the compressor rotor 29.

55 A diffuser horn 32 communicates with the accelerating flow passage 11c in the blade C and provides a pressure recovery for high velocity air discharging through the diffusers 30.

It will thus be appreciated that the two-stage compressor assembly D in the hub 10, provides a substantial 60 velocity increase to air at the hub 10 in the decelerating flow passages 11a and 11b, about to enter the accelerating flow passage 11c.

It will further be appreciated that the provision of the 65 two-stage compressor assembly D is only shown by way of preferred example, where the propeller structure P will be operated at comparatively slow speeds or under high load conditions, and that a propeller structure incorporating more or less than a two-stage, three-compressor arrangement, or some other combination thereof, might prove more advantageous for a particular installation depending on the application and operating conditions contemplated.

70 After the pressurized, high velocity air has entered the accelerating flow passage 11c in the blade C, a predeter-

mined quantity of fuel will be metered into the flow from the fuel injector or spray 21. As the air continues to advance toward the blade tip, it will receive an additional velocity increase and mixing action due to the centrifugal force effects of the blade rotation. The baffles or agitators 23 will further mix the fuel-air mixture until it is ignited by the spark gap 20. A flame front, established by the ignition from the spark gap 20 will then ignite bleed fuel in the flame holder 19, which then acts as a continuous primary ignition source for the fuel-air mixture entering the combustion chamber 18.

A plurality of cooling ducts or bleeds may be provided around the combustion chamber 18, in the leading edge portion 14c in the event conduction cooling to the atmosphere does not prove adequate.

Referring now to Figure 3, an enlarged cross-sectional view of the hub and second-stage compressor is illustrated, in conjunction with the propeller assembly accessories.

In Figure 3, the second-stage compressor 29 is shown fastened to a shaft 33 which is journalled for rotation at one end by a bushing 34 in the volute chamber 28b and hub 10, and by a bearing assembly 36 at the other end of the hub member 10. A planetary gear 37c is secured to the shaft 33 and engages an internal sun gear 38 in the face of an accessory support member E, adjacent the hub 10. As the internal sun gear 38 is rigidly fastened to the accessory support member E, rotation of the propeller structure P will induce a relative differential rotation of the compressor rotor 29, thereby increasing the velocity increment of air received from the volute chambers 28a and 28b.

The first-stage compressors 26a and 26b, are similarly splined or keyed to a shaft and planetary gear which also engages the internal sun gear 38 to provide a first-stage compression for air entering the hub from the decelerating passages 11a and 11b.

It will be appreciated that an optimum gear ratio is provided between the internal sun gear 38 and planetary gears 37a-c so as to obtain the optimum interstage compression ratio for a particular propeller assembly and application.

The propeller assembly P is secured to a main shaft 39 by a series of fasteners 40 and is rotatably journalled in the accessory support member E by a plurality of bearing assemblies 41.

The main shaft 39 has a flanged portion 42 at its propeller hub end which includes an external ring gear 43. The ring gear 43 is in toothed engagement with a spur gear 44 which connects to a starter or accumulator S, through a shaft 46, to initially rotate the propeller structure P until the jet propulsion system becomes operable. Suitable clutch means, not shown, disengage the starter S when rotation of the propeller assembly becomes self-sustaining.

An accessory drive gear 47 is secured to the main shaft 39 at its end opposite the hub member 10, by a plurality of fasteners 48. A fuel pump F engages the accessory drive gear 47 through a shaft 49 and spur gear 50. A generator or magneto G also engages the accessory drive gear 47 through a shaft 51 and spur gear 52, to provide a high potential spark to bridge the spark gap 20 in the blade C when starting the propeller assembly P.

The main shaft 39 is hollow and encloses a main fuel conduit 53, which communicates fuel from the fuel pump F through the hub member 10 and blade C to the fuel injector or spray 21 and flame holder 19.

A high potential spark conduit 54 is concentrically positioned within the main fuel conduit 53 and communicates a high potential current from the generator G through the hub member 10 and blade C to the spark gap 20.

It will thus be appreciated that the accessory support member E compactly houses the necessary accessories for the operation of the integral jet propulsion system

in the propeller assembly E so as to permit ease of maintenance, servicing or replacement, and at the same time allowing greater space for a useful pay load.

It should further be appreciated that if the present invention were utilized in conjunction with a conventional engine, as a supplementary or stand-by power source, many of the accessories and controls shown in Fig. 3 could be eliminated as they would be present in the primary power supply, thus making possible even greater weight savings and compactness.

It will be understood that many other modifications and variations may be effected without departing from the scope of the novel concepts of the present invention.

I claim as my invention:

- 15 1. A jet propelled propeller structure comprised of at least two hollow radial blades extending from a central hollow hub member and circumferentially spaced with respect to one another, leading and trailing edge portions on said blades, an air inlet in the leading edge of at least one of said blades remote from said hub, a jet exhaust outlet in the trailing edge of at least one other of said blades, a combustion chamber also in said trailing edge communicating with said exhaust outlet, a radial flow inlet passage in the hollow internal portion of at least one of the blades registering with the inlet in said blade, a radial flow outlet passage in the hollow internal portion of at least one other of the blades registering with the jet exhaust outlet in said blade, said radial flow inlet and outlet passages communicating with the hollow hub member, at least one first stage centrifugal flow compressor in said hub member having an inlet and an outlet, at least one second stage centrifugal flow compressor in said hub member having an inlet and an outlet in series with said first stage centrifugal flow compressor, means communicating the inlet of said first stage centrifugal flow compressor with a radial flow inlet passage, means communicating the outlet of said second stage centrifugal flow compressor with a radial flow outlet passage, means communicating the outlet of said first stage centrifugal flow compressor with the inlet of said second stage centrifugal flow compressor, means in said hub member for supplying fuel to air flowing through said radial flow outlet passage, and means for igniting said fuel to produce a propulsion reaction in the combustion chamber and a jet exhaust out of said jet exhaust outlet thereby causing said propeller structure to rotate.
- 20 2. A jet propelled propeller structure comprised of a hollow central hub portion, a plurality of hollow radial blades extending from said central hub portion having at least one tangential air inlet remote from said hub portion and at least one tangential jet exhaust outlet in one of said blades and forming a jet flow passage in another of said blades, said hollow blades forming a flow passage for air moving axially through each of said blades toward the jet exhaust outlet and subjecting the air to the acceleration effects of the centrifugal force induced by the rotation of said propeller structure, said central hub portion enclosing a two-stage centrifugal flow compressor system, at least one first stage centrifugal flow compressor registering with a radial flow passage in one of the blades and receiving air therefrom, at least one second-stage, centrifugal flow compressor registering with a radial flow passage and receiving initially compressed air from said first stage centrifugal flow compressor, and fuel addition, mixing, means supplying fuel to air flowing through said blades, and means for igniting said fuel to increase the jet velocity of air moving tangentially out of said jet exhaust outlet causing the propeller structure to rotate.
- 25 3. A jet propelled propeller structure comprising a plurality of hollow radial blade members extending from a central hub member and forming a radial jet flow passage therethrough spaced inwardly of the leading and trailing edges of each of the blades, leading and

trailing edge portions on said blades, at least one peripheral inlet in the leading edge of one of the blades, at least one peripheral jet exhaust outlet in the trailing edge of one of the blades, means for supplying fuel to air flowing through said radial flow passage, and means for igniting said fuel to provide a jet exhaust out of said jet exhaust outlet, a two-stage centrifugal flow compressor in said hollow central hub member to additionally pressurize air flowing through said radial flow passage from the inlet to the jet exhaust outlet, thereby increasing the jet velocity of air moving out of said jet exhaust outlet.

4. A jet propelled propeller structure, comprised of a plurality of hollow radial blades extending from a hollow central hub member, leading and trailing edge portions on said blades, at least one peripheral tangential air inlet in the leading edge portion of one of said blades, at least one tangential jet exhaust outlet in the trailing edge portion of one of said blades, the air in said hollow blades moving toward the jet exhaust outlets being subject to the acceleration effects of the centrifugal force induced by the rotation of said propeller structure, flow passages spaced inwardly of the leading and trailing edges of each of the blades and extending axially therealong said tangential air inlet and jet exhaust outlet communicating with the hollow central hub member through the flow passages in said blades means for supplying fuel to air flowing through said blades, and means for igniting said fuel, a two-stage, centrifugal flow compressor in said hollow central hub member, said two-stage centrifugal flow compressor having at least one first-stage element and one second-stage element arranged in said hollow central hub member in balanced relationship for rotation with said propeller structure and receiving air from the tangential air inlet in at least one of the blades, said compressor supplying additionally compressed air at the internal hub end of at least one of the blades having a tangential jet exhaust outlet, each inlet of the double-entry second-stage centrifugal flow compressor receiving initially compressed air from at least one first stage centrifugal flow compressor, thereby providing an additional increase in pressure and velocity to air moving from the tangential air inlet toward the tangential jet exhaust outlet serving to rotate said propeller structure.

5. A jet propelled propeller structure comprised of a plurality of hollow radial blades extending from a hollow central hub member, leading and trailing edge portions on said blades, at least one peripheral tangential air inlet in the leading edge portion of one of said blades, at least one peripheral tangential jet exhaust outlet in the trailing edge portion of one of said blades, guide means in said inlet directing the airflow inwardly and axially of the blade, the air in said hollow blades moving toward the jet exhaust outlet being subject to the acceleration effects of the centrifugal force induced by the rotation of said propeller structure, flow passages spaced inwardly of the leading and trailing edges of each of the blades and extending axially therealong, said tangential air inlet and jet exhaust outlet communicating with the hollow central hub member through the flow passages in said blades, means for supplying fuel to air flowing through said blades, and means for igniting said fuel, a two-stage centrifugal flow compressor having at least one first stage element and one second stage ele-
